UNITED STATES PATENT OFFICE.

FRANK A. SCHOENL, OF CLEVELAND, OHIO, ASSIGNOR OF ONE-HALF TO HUDSON K. DE LLOYD, OF CLEVELAND, OHIO.

CLOTH-HOLDING DEVICE.

1,297,016.

Specification of Letters Patent. Patented Mar. 11, 1919.

Application filed June 24, 1918. Serial No. 241,513.

To all whom it may concern:

Be it known that I, FRANK A. SCHOENL, a citizen of the United States, residing at Cleveland, in the county of Cuyahoga and State of Ohio, have invented certain new and useful Improvements in Cloth-Holding Devices, of which the following is a specification.

This invention is a device or attachment particularly adapted for the use of a seamstress or tailor, for the purpose of holding work while operating thereon. For example, it may be used to hold cloth while it is being ripped or cut, or while basting threads are being cut; and it may also be used to hold one end of a piece of work while it is being sewed or otherwise worked upon.

The device comprises a clamp which may be fixed to the top of a sewing machine or other table, and this clamp is provided with a support or projection to receive pins whereby the cloth may be fixed to said support and held in a raised position above the surface of the table. The construction of the device would be more fully evident from the accompanying drawings and the following description.

In the drawings, Figure 1 is a side elevation of the device. Fig. 2 is a top plan view thereof.

Referring specifically to the drawings, 6 indicates a U-shaped clamp frame, the lower arm of which is provided with a screw 7 by means of which it may be secured to the edge of a table 8 or the like, as shown in Fig. 1. The upper arm of the clamp, which fits upon the upper surface of the table, is extended at its end to form a vertical or upright standard or part 9, at the top of which is a disk or head 10, extending horizontally. The clamp frame, standard and disk, may conveniently be made of a single piece of heavy sheet metal, cut and pressed to the desired shape, and by the means shown and described, the disk 10 is supported above the surface of the table.

Means are provided for fastening a piece of cloth or other work to the top of this head or disk. As shown, the means consist of pins 11 which can be inserted through or under bosses 12 which are cut and struck

up from the metal of the disk, the pins being inserted through slits or openings at the ends of the bosses, whereby the pins are retained in place. As shown in Fig. 2, these bosses may extend in two or more directions. As shown, two pairs of bosses are arranged to extend in one direction and another pair 12^a to extend at a right angle thereto. Accordingly, the pin or pins can be inserted in either direction at the convenience of the operator.

When the pins are so inserted, the cloth may be hooked or engaged therewith and then stretched over the surface of the table, 65 the device holding one end of the cloth and the hand of the operator holding the other end. In ripping a seam for example, one end of the seam can be engaged with this attachment and the other end held by the operator in one hand, and the ripping knife drawn quickly along the seam. Any other work may be held in a similar manner, and the cloth can either be engaged over the projecting ends of the pins, or can be pinned 75 to the disk between the bosses.

The device will be found very useful for the intended purpose, and modifications may be made in the structure, within the scope of the invention.

I claim:

1. A device of the character described, comprising a clamp having upper and lower arms, the former having a vertical standard thereon, a head at the top of the standard, projecting horizontally therefrom, and a pin engageable with the head and adapted to fasten a piece of work thereto.

2. A device of the character described, comprising a clamp having a frame with parallel arms one of which has a standard at one end and a laterally projecting head supported thereby, the head being provided with perforated bosses adapted to receive a pin to attach a piece of work thereto.

In testimony whereof, I do affix my signature in presence of two witnesses.

FRANK A. SCHOENL.

Witnesses:

JOHN A. BOMMHARDT,
HUDSON K. DE LLOYD.
